UNITED STATES PATENT OFFICE.

CHARLES E. REID, OF KANSAS CITY, MISSOURI.

ELEVATOR FOR LETTERS, &c.

SPECIFICATION forming part of Letters Patent No. 426,418, dated April 22, 1890.

Application filed September 27, 1888. Serial No. 286,492. (No model.)

To all whom it may concern:

Be it known that I, CHARLES E. REID, a citizen of the United States, residing at Kansas City, in the county of Jackson and State 5 of Missouri, have invented new and useful Improvements in Elevators for Letters and other Articles, of which the following is a specification.

This invention relates to elevators for the 10 conveyance of letters and packages from a lower to a higher story in dwellings and other buildings, so that letters and other articles dropped into the elevator in the lower story can be raised to such higher story with facility. It is intended that each story shall have 15 its own elevator and its own separate well, as is provided also in my previous patent, No. 302,776, dated July 29, 1884. The letter or article to be taken up is deposited by the postman in the carrier of the elevator through the hinged door, and his action in opening the door of the drop-box causes a signal to be given on the floor where the top of the elevator is situated. The occupant of such floor 20 then operates the elevator so as to bring up the carrier, to which he can obtain access through a door placed in the upper part of the well. Having taken out the letters from the carrier, the operator walks away. The spring-door 25 of the carrier being released, the door immediately closes, thereby releasing the carrier, as hereinafter explained, when the carrier descends automatically to its former position on the lower story, ready for another operation. 30

The peculiar and novel construction of my improvement is described and pointed out in the following specification and claims, reference being had to the accompanying drawings, in which—

Figure 1 is a front elevation, partly in section, showing the improvement applied to a house having several stories, each story being provided with its separate well and elevator. 45 There is a stack of four elevators or wells represented in the figure, the elevator situated on the right-hand side in the said figure extending up to the second story, where the partition-wall is broken away to show the hoisting apparatus that appertains to that elevator. Fig. 2 is a vertical section on the line 50 $\alpha\alpha$ of Fig. 1, showing the carrier in position

in the lower part of the well to receive letters from the drop-box. Fig. 3 is an elevation of the hoisting apparatus and carrier of one of 55 the elevators. Fig. 4 is a vertical section of part of the hoisting apparatus taken on the line $y\ y$ of Fig. 3. Fig. 5 is a vertical section of the pulley at the top of the hoisting apparatus taken on the line $u\ u$ of Fig. 3. Fig. 6 60 is a sectional view taken on the line $x'\ x'$, Fig. 8, showing the spring-stop to arrest the carrier. Fig. 7 is a sectional view taken on the line $x^2\ x^2$, Fig. 6. Fig. 8 is a sectional view taken on the line $x^3\ x^3$, Fig. 7; and Fig. 9 is a 65 sectional view taken on the line $x^0\ x^0$, Fig. 2.

Similar letters and figures indicate corresponding parts.

In the drawings, the letter A designates the elevator-wells, in each of which is to be placed 70 a carrier B. A stack of four such wells is represented in Fig. 1. They are all constructed substantially in the same manner, except that they vary in length, as they are carried to different stories of the building. Each 75 is provided with such a carrier B, which runs up and down in the well, being drawn up by a hoisting apparatus C, that is mounted on the wall alongside or convenient to the upper part of the well, as is represented in Fig. 80 1, where the wall or partition D, which covers the hoisting apparatus, is removed. Each of the other wells is provided with a similar hoisting apparatus located near the upper 85 end of the well; but they do not appear in Fig. 1, because the figure does not represent the other wells above the second story.

The wells A are preferably made fire-proof.

In Fig. 2 is shown the lower part of a well, in which is seen the carrier B, resting on the 90 upper edges of a platform E, which is supported on a spring F, whose lower end rests on a fixed partition G, extending across a casing H, fitted in the lower part of the well. The platform E is adapted to slide in the casing H as far down as the shoulder I. The platform E consists of a frame whose vertical sides are connected by a horizontal piece. The height to which the platform E can be pushed upward by the spring F is limited by 95 the shoulder J in the sides of the well A. The carrier B in its lower position (see Fig. 2) comes opposite a glass window K, made in one of the sides of the well, and a similar window 100

L is provided in the corresponding side of the carrier, so that the interior and the contents of the carrier can be seen through the two windows. The lower door K has a lower 5 pane extending nearly across its width, and above such lower pane four smaller panes. The several panes are divided by strong cross-bars or muntins, which will prevent a thief who may break the glass from inserting his 10 hand and abstracting the contents of the carrier. The lower pane enables one to see if there is any mail in the carrier, even if the tablet hereinafter mentioned is present therein, as the tablet will be opposite the smaller 15 panes. The carrier is also provided on one of its sides with a slide M, by means of which access is had to the interior of the carrier to remove its contents when it has been moved up to the proper floor.

20 One of the objects of the arrangement of the windows K L, as described, is to use the carrier as a means of informing callers and friends of the absence of the occupants. For example, the occupant, having prepared cards 25 or tablets of suitable size, writes upon one of them information of his contemplated absence from home, and, having raised the carrier up to the floor of his apartment, lifts the slide and places the tablet in the carrier with its written 30 face against the glass of the window L. The carrier, having then descended with the tablet to the lower floor, presents the written face of the tablet to those persons who may enter upon that floor, and they become aware 35 of the contents of the message. Thus, if a family is leaving their apartments and expect callers to whom they wish to convey any message, they can do so by means of the carrier, as described. In like manner correspondence in cases of sickness or contagious 40 disease in any given family in an apartment-house can be carried on between members of such family and those of any of the other families in the house, provided they station 45 themselves at the lower point of access to the elevator-well, where the tablet can be read when the carrier is at rest below. The carrier is preferably constructed to engage and be guided by vertical grooves O in a wall A.

50 The carrier B, as represented in Fig. 2, is in position to receive letters or other articles, its front side, which is lower than its other sides, being opposite the drop-box P, which is placed in and over an opening made for that 55 purpose in the lower part of the well. The drop-box P is provided with an inlet Q, which is kept closed by an inner door R, which door is opened by suitable devices and is closed by means of the weight of arm 4. Letters or 60 articles introduced through the inlet Q pass into the carrier over the inclined plane U.

Before the door R has been opened as far as the star (*) the arm T has been moved against the lever V far enough to turn the bell-crank 65 V W, and thereby pull the bell-wire X and ring the bell Y, (seen in Figs. 1 and 3,) and at the same time, if desired, to operate a visual

annunciator, (seen in Figs. 6 and 8,) the arrangement being such that no mail-matter or other article can be inserted through the drop-box into the carrier until the bell has been rung, as the door R does not reach the place of star (*) until after the alarm has been sounded.

The hoisting apparatus is fixed in a receptacle 5 in the story to which the carrier is to be hoisted, and consists in a driving-wheel 6, which is turned by a crank 7, arranged to be folded in a recess 8 in the wall when not in use. The wheel 6 is fast on its shaft, and it 75 has on one side a series of cogs 9, which are engaged at certain times by a brake-arm 10, so as to stop the revolution of wheel 6 and the connected wheels. This is done automatically, as will be below explained. The periphery of wheel 6 is by preference coated with leather and is in contact with the periphery of wheel 11, which is by preference coated with rubber. The wheel 11 is fast on shaft 12, and said shaft is mounted in spring-bearings 80 so arranged as to be pressed continually downward, whereby the wheel 11 is pressed continually against wheel 6. Upon the same shaft 12 is fixed the pulley 13, from which extends the round leather band 14, which passes 85 around the small pulley 15 and transmits motion to its shaft 16, on which shaft is also fixed the drum 17.

The top of the carrier B is provided with a strengthening-bar 18 across its top and with 90 a bail 19, to which is fastened one end of a rope 20, around which is secured a disk 21, on which rests the flaring mouth 22 of a tube 23, which extends upward through the casing 24. The rope 20 is conducted upward through the 95 tube 23, and thence around the pulley 25 and down to drum 17, to the face of which it is fastened. Around the lower part of the tube 23, and resting on the top of its flaring mouth, is placed a spiral spring 26, whose upper end 100 bears against the bottom of the casing 24. The top of tube 23 is provided with a disk 27, to which is fastened a cord 28, which is conducted thence downward to the brake-arm 10, to whose free end it is secured. The other 105 end of the brake-arm is secured by a hinge-joint to the frame in which the hoisting apparatus is placed.

The operation of the hoisting apparatus is as follows: The occupant of the floor, who has 110 been signaled to, operates the hoisting apparatus, and thereby hoists the carrier B with great speed, the several wheels being arranged as shown for that purpose. When the disk 21 of the carrier strikes the flaring mouth 22 115 of the tube 23, it suddenly compresses the spring 26 and produces slackness in the cords 20 and 28 and allows the brake-arm 10 to fall upon the cog-wheel 6 between adjoining cogs, and thereby stop the wheel and prevent it 120 from turning in either direction. While the carrier is being hoisted the rope 20 is wound upon the drum 17 as the carrier is being drawn up. In order to prevent the rope 20 from be-

ing thrown off from pulley 25 when slackness is suddenly made on the rope, I fasten to each side of the pulley a metal rim 29 29, which is annular, revolves with the pulley, and projects 5 beyond the entire periphery of the latter, and is then contracted, and is then bent outward, so that when the rope is momentarily thrown upward it will strike the sides of the rim and be guided back to its place on the pulley.

10 When the carrier has been hoisted, it is allowed to rest upon the spring-stop 30, (see Fig. 6,) which is hinged at its lower end at 31 in a recess in the side of the well, while its upper end is pushed outward by a spring 32.

15 An anti-friction roller 33 is placed at the upper end of the stop on its outside to allow the carrier to move past it with very little friction. The stop 30 is represented in Figs. 6, 7, and 8. When the carrier is up in its higher 20 position, the door 34 is thrown open to allow access to the carrier to remove its contents. When the door is being closed, the bent arm 35 strikes the jointed spring-lever 36, whose longer arm engages with the upper end of the 25 spring-stop and suddenly withdraws the latter inward from beneath the carrier and the carrier falls to its lower position, the arm 35 meanwhile passing the lever 36 and allowing it to resume its normal position (shown in Fig. 30 11) ready for a repetition of the operation when the door is again shut. It is obvious from the drawings that the opening of the door will not operate the lever 36 nor act on the stop 30.

35 The carrier is intended to fit the well A in cross-section, but not so closely as to hinder it from moving easily therein. To prevent it from descending too rapidly therein, I secure to its bottom a sheet of felt 37, which is of 40 such size as to extend a little beyond the bottom edges of the carrier and to come in contact with the sides of the well. I may also for the same purpose provide an air-cushion in the well by making air-holes 38 through the 45 bottom 39 of the well and form in the well an air-chest 40, in whose side I make air-openings 41, that are covered by valves 42, that are arranged so that they can swing open inwardly. The top of the air-chest communicates with the well by means of openings 43, made through the partition G and the platform E. By these means air is admitted within the well and in the parts below it, and its too 50 speedy escape before the descending carrier

is prevented. The fall of the carrier on the 55 platform is further controlled by the spring F under the platform E.

The various door and window openings are so made and arranged as to be readily removed to give access to the operative parts in 60 the well.

What I claim as new, and desire to secure by Letters Patent, is—

1. In elevators for letters and other articles, the combination of the carrier B, the 65 hoisting apparatus composed of the driving-wheel 6, provided with cogs 9, the crank 7, wheel 11, adapted to engage wheel 6, pulley 13, band 14, pulley 15, drum 17, rope 20, brake-arm 10, the cord 28, and the connections between said cord 28 and the carrier B, constructed and operated substantially as described.

2. In an elevator for letters and other articles, the combination, with the carrier B, 75 suspended on the rope 20, which connects the carrier with the hoisting mechanism, of the pulley 25, provided with attached annular rims 29, which revolve with the pulley and are contracted toward each other beyond 80 the rope-carrying periphery of the pulley, to prevent the rope from being thrown off the pulley at any point when the rope is thrown upward in a direction away from the pulley, substantially as described. 85

3. In elevators for letters and other articles, the combination, with the carrier B, of rope 20, yielding tube 23, cord 28, and brake-arm 10, the carrier being suspended by rope 20 from drum 17 of the hoisting mechanism, 90 substantially as shown and described.

4. In an elevator for letters and other articles, the combination of a well A, having an opening provided with a hinged door 34, a carrier B, hoisting mechanism for the carrier, 95 a spring-stop 30, for supporting the carrier, and a lever 36, connected at one end with the stop and acted on at the other end to retract the stop when the hinged door is swung to close the opening in the well, substantially as 100 described.

In testimony whereof I have hereunto set my hand in the presence of two subscribing witnesses.

CHARLES E. REID.
